UNITED STATES PATENT OFFICE

2,363,518

DOMESTIC APPLIANCE

Donald K. Ferris, Dayton, Ohio, assignor to General Motors Corporation, Dayton, Ohio, a corporation of Delaware

Application November 30, 1940, Serial No. 367,989

10 Claims. (Cl. 38—54)

This invention relates to domestic appliances and more particularly to ironing machines.

An object of this invention is to provide an ironing machine with a unitary control causing rotation of one of the ironing members, closure of the gap between the ironing members, rotation or non-rotation of one of the ironing members when they have been closed upon each other, and a change of speed of rotation of one of the ironing members.

Another object of my invention is to provide an ironing machine capable of being selectively specialized for ironing flat work or wearing apparel.

Another object of this invention is to provide an improved mechanism for driving the rotatable ironing member and for closing the shoe upon the rotatable ironing member.

Another object of this invention is to provide an ironing machine with a relatively large shoe and a relatively small shoe, which cooperate with each other to specialize the machine selectively for ironing flat work or wearing apparel.

Further objects and advantages of the present invention will be apparent from the following description, reference being had to the accompanying drawings, wherein a preferred form of the present invention is clearly shown.

In the drawings:

Fig. 1 is a vertical view, partly in cross-section, of my ironing machine;

Fig. 2 is a top view of a portion of the ironing machine;

Fig. 3 is a rear view of a portion of the ironing machine;

Fig. 4 is a vertical view, partly in cross-section, taken transversely to Fig. 1;

Fig. 5 is an end view of the upper part of the ironing machine showing both shoes retracted;

Fig. 6 is a view, somewhat similar to Fig. 5; but showing one of the shoes closed upon the rotatable iron member;

Fig. 7 is a vertical cross-section showing the transmission mechanism;

Fig. 8 is a horizontal cross-section taken along the line 8—8 of Fig. 7;

Fig. 9 is a horizontal cross-section taken along the line 9—9 of Fig. 7;

Fig. 10 is a vertical cross-section taken along the line 10—10 of Fig. 8;

Fig. 11 is an elevational view of the mechanism shown in the lower part of Fig. 7;

Fig. 12 is a bottom view of a portion of the mechanism shown in Fig. 11;

Fig. 13 shows a detail of the mechanism shown in Fig. 11;

Fig. 14 is a horizontal cross-section taken along the line 14—14 of Fig. 11, showing the station clutch just before release of the shoe actuating cam from the drive mechanism;

Fig. 15 is a view similar to Fig. 14, but showing the cam in its fully released position;

Fig. 16 is a horizontal cross-section taken along the line 16—16 of Fig. 7;

Figs. 17, 18, 19 and 20, show the control pedal and its associated parts in the "stop," first speed, second speed and "press" positions respectively;

Fig. 21 is an exploded view, in perspective, of the station clutch mechanism; and

Fig. 22 is a horizontal cross-section taken along the line 22—22 of Fig. 7.

The ironing machine may be mounted on a standard or table 10. It is provided with a rotatable ironing member or roller 11, a shoe structure including a relatively large shoe 12 and a relatively small shoe 13. The ironing members are closed upon and opened from each other and the ironing members are movable with respect to each other codirectionally to the surface of the large shoe. To this end, the rotatable member 11 is rotated under the control of a unitary controlling member or pedal 14. The arrangement is such that the pedal 14, in various positions, causes either or both of the shoes to be closed upon the roller 11, causes the roller 11 to rotate at a plurality of speeds, or may cause the roller to remain stationary when the shoe structure has been closed upon it for pressing operations.

A motor 15 is provided for furnishing power to the parts controlled by the pedal 14. The motor 15 is connected to those parts through the medium of a transmission in the casing 16. This transmission is controlled by the pedal 14 to cause the roll driving shaft 17 to rotate at first and second speeds, and to rock the shoe actuating shaft 18 to bring the shoe structure into engagement with the roller 11.

The roller 11 is mounted on a stationary bearing shaft 19 and is driven by means of a rotatable shaft 20 keyed to the roller 11 at 21 and geared to the shaft 17 at 22.

The shoe structure is mounted on the rockable shaft 18. The large shoe 12 is secured to backwardly directed lugs 23 which are fulcrumed at 26 on the lever structure 24, which is loosely mounted on the shaft 18. Lever structure 24 is U-shaped in horizontal cross-section. A locking lever structure 25 is also fulcrumed at 26 and is provided with an extension 27 which may be

brought into engagement with the end 28 of a leaf spring 29, the other end 30 of which is keyed and secured in the shaft 18. The arrangement is such that, when the lever structure 25 is pulled towards the user or to the left as viewed in Figs. 1 and 6, by means of the knob 31, the corresponding shoe is placed in condition for engagement with the roller 11 whenever the shaft 18 is properly rocked by the transmission mechanism. Another leaf spring 29' is keyed to the shaft 18 and is effective to retract the shoe when the shaft 18 is rocked clockwise. A more detailed showing and description of the shoe supporting mechanism is contained in my copending application S. N. 282,228 filed June 30, 1939 to which reference is made, if necessary, for further disclosure thereof.

Means are provided for stopping the backward movement of the lever 24. To this end, the sides of the lever 24 are provided with openings 124 and a bar 125 is secured to the sides 20 of the lever 24. This bar 125 strikes against spring 28 and prevents the lever 24 from falling too far back when released by the handle 31.

The small shoe 13 is supported on the shaft 18 by a structure similar to that which supports the shoe 12. Corresponding parts have been numbered with the same number provided with the suffix *a*.

The large shoe 12 and the small shoe 13 are of substantially the same length along the circumference of the roll. They are separated by a slanting division 13a, which is advantageous for reasons given in my said copending application. They may be selectively brought separately into engagement with the roller, or they may both be brought together into engagement with the roller by movement of the knobs 31 and 31a towards or away from the user and by subsequent movement of the pedal 14 to cause the motor to rock the shaft 18. When brought forward together, they form a large composite shoe useful in ironing flat work. The small shoe alone is specially adapted for ironing the collars, cuffs, sleeves, etc., of wearing apparel. The slanting edge of shoe 12 along division 13a is also useful in ironing collars and the like of wearing apparel, when the large shoe 12 is being used without the small shoe. However, it is more advantageous to use the small shoe for this purpose.

The shoe rocking shaft 18 is journalled in a stationary bearing 40 carried by the upstanding casing 41. The roller 11 and its stationary bearing 19 are carried by the stationary casing 42, both cases being rigidly secured to each other and to the base 18, through the medium of the solid top 18a of the gear casing 16.

The shoe rocking shaft 18 is rocked by a downwardly extending lever 43. The lower end 44 of the lever 43 is rocked by the extension 45 of the cam sleeve member 46. The cam sleeve member 46 is actuated by the cam 47, which may be rotated selectively to two positions, around stationary stub shaft 41a, by means of a station clutch arrangement hereafter described. The station clutch includes a ratchet wheel 48 which rotates all the time that the motor 15 is actuated. The ratchet wheel 48 is engaged by the tooth 49 while the cam 47 is being moved between its "station" positions, and the tooth 49 is automatically disengaged from the ratchet wheel 48 at the "stations" when the shoe structure is either fully retracted or fully brought forward. The station engagement and disengagement of the tooth 49 is controlled by means

5 of the rotating levers 50 which come into the engagement with the end 51 of the rockable stop lever 52. As shown in Fig. 14, one of the levers 50 has just come into engagement with the end 51 of the lever 52. Referring to Fig. 21, along with Figs. 14 and 15, it is to be noted that the tooth 48 is carried by a slide 53 which fits over the cam 47 and is slidably secured thereto by means of screws 54 with the plate 55 interposed therebetween. Accordingly, when the ratchet wheel 48 rotates the tooth 48, slide 53, plate 55 and cam 47 in a counter-clockwise direction for a short distance after the lever 50 engages stop 51, the pin 56 is rotated relatively to the now stationary slot 57, causing the slide 53 to move outwardly (to the left in Figs. 14, 15 and 21). At the same time the tension on spring 58 is stretched between the now stationary ear 59 of the plate 55 and the moving lug 41a rotating cam 47. This relative motion continues between the position shown in Fig. 14 to that shown in Fig. 15 at which time the cam 47 and plate 55 stop rotation because the tooth 49 becomes disengaged from the driving ratchet wheel 48.

It is to be noted that the slot 57 is wider than the diameter of the pin 56, as clearly indicated in Figs. 14 and 15. This prevents ratcheting of the tooth 49 with the ratchet 48 after the mechanism has reached the position shown in Fig. 15, because the tooth 49 can be knocked clear of the teeth of ratchet 48 due to the clearance play between pin 56 and slot 57.

The cam is maintained in the position shown in Fig. 15, by a leaf spring 60, carried by the sleeve 46, which spring 60 engages the teeth 61 formed in the periphery of the cam 47. These teeth are constructed to allow the cam 47 to move counter-clockwise with relation to the sleeve 46, but prevent backward movement thereof. The station stop is so selected that the cam 47 stops slightly before maximum outward movement of the sleeve 46 is produced, and at this time the tooth 49 is released. The leaf spring 60 then prevents backward movement of the cam 47 in spite of the strong backward pull by the spring 58 between the ear 59 and the cam 47.

The motor 15 drives the worm 62 which is meshed with the gear 63 and drives the shaft 64. This shaft is fixedly secured to the ratchet wheel 48 and also to a sun gear 65 which is part of a planetary gear drive for the roll rotating shaft 17. The planetary gearing is so constructed that when the toothed ring 66 is stopped by the lever 67, the roll is rotated at one speed. When the toothed wheel 68 is stopped by the lever 69, the roll is rotated at a different speed. The levers 67 and 68 are urged in a clockwise direction by springs 70 and 71 and in a counter-clockwise direction (Figs. 8 and 9) by the slide 60 72 under the control of pedal 14. The slide 72 is provided with a notch 73, such that when the notch 73 is brought into positions opposite the ends of levers 67 and 68 respectively, the respective levers are permitted to be rocked clockwise 65 by their respective springs 70, 71, into stopping engagement with the respective wheels 66 and 68. Thus it is to be seen that when the pedal 14 is moved to its various positions (see Figs. 17, 18, 19 and 20) the planetary gears are controlled by 70 the levers 67 and 68 to hold the roll 11 in the stopped position when the pedal 14 is in its uppermost and lowermost position, and the roll 11 is rotated at first and second speeds when the pedal 14 is in its two intermediate positions. It is to be noted that the shoes 12 and 13 may

be used together as a unitary large shoe by moving the handles 31 and 31a forward to cause the leaf springs 28 and 29a to become effective on their respective shoes. Either one of the shoes 12 or 13 may be used independently of the other by moving one of the handles 31 or 31a forward while the other handle is in the back position. The small shoe 13 is particularly useful for ironing wearing apparel such as shirts or the like, and may be used with the same effect as a hand iron without the necessity of lifting the same. Because of the shape and size of the shoe 13, it is possible to iron collars, cuffs, etc., with very little practice and in a manner quite similar to hand iron operation.

The two-speed planetary drive is connected to the shaft 17 by means of the spider 80 which is fixed to the shaft 17. The spider 80 carries gears 81 mounted on bearing pins 82. The gears 81 are meshed with the sun gear 65 and also with an internal gear 83 carried by the wheel 66. The gears 81 have integrally formed therewith smaller gears 84 which mesh with an internal gear 85 on the wheel 68. The wheels 66 and 68 are loosely mounted on bearings 86 and 87 respectively so that they are free to turn as long as they are not engaged by the stop rods 67 and 69. Therefore, as long as these rods are disengaged, no torque can be transmitted through the free running wheels 66 and 68, and the shaft 17 remains stationary. However, when the wheel 66 is held stationary, a relatively fast rotation is imparted to the roll 11, while a relatively slow rotation is imparted to the roll 11 when the wheel 68 is held stationary.

The station clutch is controlled from the pedal 14 by means of the slide 72. The slide 72 is provided with an ear 90 on top of which the end 91 of the stop lever 52 rests. The stop lever 52 is urged in a clockwise direction (Fig. 7) by means of the spring 92. When the slide 72 is in its highest position, as shown in Fig. 7, the end 51 of the lever 52 stops the lever 50 which holds the shoe structure away from the roller. As the slide 72 is moved to its next lower position, the end 51 of the lever 52 rises to engage the upper lever 50 and thus moves the station clutch structure to hold the shoe structure against the roll.

It is desirable to provide an "indexing" means so that the user may be conscious of the correct place to stop the pedal 14. To this end a U-shaped spring 94 is secured to the lower portion 95 of the casing 16. This U-shaped spring contracts into the notches 96, 97 and 98 in the slide 72. This cooperation between the spring 94 and the notches 96, 97 and 98 imparts an "indexing" feel to the user's foot, so that the pedal 14 is used in the four positions only.

Means are provided for raising the pedal when released by the user's foot. To this end a spring 100 is secured to a stationary part of the ironing machine, such as to the lug 101 of the casing 16, and the other end of the spring 100 is secured to an intermediate part 102 of the rod 103 which connects the pedal 14 to the slide 72. The rod 103 is connected to the slide 72 by means of a bolt 104. The slide 72 is held from lateral displacement by the bolts 105 which are loosely fitted in the slots 106 of the slide 72 and are carried by stationary parts of the casing, such as the lug 101 and a stationary extension 107 of the transmission casing.

The transmission casing 16, which carries the roll and shoe structures may be secured to the

table 10 by any suitable means. Preferably an angle iron structure 110 is bolted, by bolts 111 to the casing 16. This angle iron structure is secured to the table supports by any improved manner, and preferably extends longitudinally along each long edge of the table from one leg to the other, to provide a rigid support for the ironing mechanism.

In the operation of the machine and assuming that the motor has been placed in motion with the manipulator 14 and slide 72 in the position thereof shown in Fig. 17, shaft 64 and gear 63 are rotated. In this position of the pedal or manipulator 14, no motive power is transmitted to roll 11 due to the fact that neither of the running wheels 66 and 68 are held, by stop rods 67 and 69, against rotation and the station clutch transmission maintains the shoes 12 and 13 in a position away from the roll. Upon placing work in association with roll 11 to be ironed, the pedal 14 is depressed to its first position of the depression as shown in Fig. 18. This movement of pedal 14 lowers the slide 72, permits lever 52 to rotate crosswise and set the station clutch transmission in motion to move both or one or the other of the shoes 12 and 13 into engagement with the roll 11 while at the same time operating one of the levers 67 or 69 into engagement with one of the wheels 66 or 68 so that power is transmitted from the motor to the roll shaft 11 to rotate the roll at one or a first speed. The material to be ironed is started between the shoes 12 and 13 and the roll 11 and if it is desired to increase the speed of the roll, the pedal 14 is again depressed to its second position of depression as shown in Fig. 19. This further depressed position of the pedal 14 causes slide 72 to axially rotate the levers 67 and 69 so that the one lever will be disengaged from holding position and the other will be brought into engagement with its associated toothed wheel to thereby cause rotation of the larger gears 81 to drive the spider 80 and consequently the roll shaft 11 at a second or increased speed. When the ironing operation is finished, pedal 14 is released. Release of the user's foot from pedal 14 renders the spring 100 effective to move the slide 72 and pedal 14 upwardly to the normal position as shown in Fig. 17 and the motor still being operated will, through the station clutch transmission, cause the shoes 12 and 13 to move back away from roll 11 in order to place the ironing machine in readiness to receive further work to be ironed or pressed. The indexing means, which conveys to the user's foot on pedal 14 sensations to render the user conscious of the various operating positions of the slide to carry out the functions of the machine, permits the user to reverse the operations of the machine described or to carry these operations forward selectively as may be desired. If it is desired to press clothes without rotation of the roll 11, such clothes are placed on the roll, and the pedal is depressed to the position shown in Fig. 20. This places the levers 67 and 69 in a position to maintain the roll stationary and moves the lever 91 to a position to rock the shoe or shoes to press the clothes. Thus the plurality of functions of the machine, through the medium of the gear transmission, station clutch transmission and connections with the slide, may be caused to be carried out by a single control or manipulator.

While the form of embodiment of the invention as herein disclosed, constitutes a preferred

form, it is to be understood that other forms might be adopted, all coming within the scope of the claims which follow.

What is claimed is as follows:

1. An ironing machine, comprising a rotatable ironing member, a shoe ironing member, a motor, a transmission between said motor, shoe ironing member and rotatable member and having means to drive rotatably said rotatable ironing member and to bring said members together, a single manipulator, connections between said manipulator, motor and transmission effective in one position to render said rotatable member stationary, in another position to rotate said rotatable member at a first speed and to bring together said ironing members, in another position of said manipulator to rotate said rotatable ironing member at a second speed, with said ironing members together, and in another position to cause said ironing members to be together with said rotatable ironing member in a stationary condition.

2. An ironing machine comprising a rotatable ironing member, a shoe ironing member, a motor, a transmission between said motor and said ironing members and having means to drive rotatably said rotatable ironing member and to bring said members together, a single manipulator, connections between said manipulator, motor and transmission, effective in one position of said manipulator to render said rotatable ironing member stationary with said shoe ironing member retracted, in another position to rotate said rotatable ironing member with said shoe ironing member closed upon said rotatable ironing member, and in another position to disconnect said transmission between said rotatable member and said motor with said shoe member closed upon said rotatable ironing member.

3. An ironing machine comprising a rotatable ironing roll member, a plurality of arcuate shoes, means to cause relative closing and opening movement between said roll member and shoes, a motor, a worm transmission driven from said motor, differential speed gears connected to said worm transmission and said rotatable ironing member, a station clutch connected to said worm transmission and controlling the relative closing and opening movement between said roll member and said shoes, and a single control means selectively to control in a plurality of positions, the differential speed of rotation of said roll through said gears and the relative closing movement between said roll member and both of said shoes or one only of said shoes and in another position to maintain said roll stationary and control the relative closing movement between said roll member and both of said shoes or one only of said shoes.

4. An ironing machine comprising a rotatable ironing roll member, a plurality of arcuate shoes mounted to move to and away from said roll member, a motor, a two-speed transmission drive between said motor and roll member, a station clutch transmission between said motor and shoes to move said shoes to and away from said roll member, a single control means to make said station clutch transmission effective selectively on said shoes and effective to control said two-speed transmission drive and release means to render said control means ineffective on one of said shoes.

5. An ironing machine comprising a rotatable ironing member, a shoe member, said members

being relatively movable to and from each other, and a station clutch for relatively moving said members to and from each other, including a rotatable cam, a cam sleeve, a toothed slide, a rotatable ratchet wheel, a lever plate having means to move said toothed slide into engagement and disengagement with said ratchet wheel, a spring between said cam and lever plate, and a one-way lock between said cam sleeve and cam to prevent backward motion of said cam when said toothed slide is disengaged from said ratchet wheel.

6. An ironing machine comprising a rotatable ironing member, a movable shoe, a motor, a rotating transmission between said motor and rotatable ironing member, a station clutch transmission between said motor and shoe, a pedal, and connecting means between said transmission and pedal effective in one position of said pedal to disengage both of said transmissions, in another position of said pedal to engage said rotatable transmission to rotate said ironing member and to engage said station clutch transmission to move said shoe against said ironing member, and in another position of said pedal to disengage said rotating transmission to maintain said rotatable ironing member stationary and to engage said station clutch transmission to cause said shoe to be against said ironing member.

7. An ironing machine comprising a rotatable ironing member, a movable shoe, a motor, a rotating transmission between said motor and rotatable ironing member, a station clutch transmission between said motor and shoe, a pedal, connecting means between said transmissions and pedal effective in one position of said pedal to disengage both of said transmissions, in another position of said pedal to engage said rotatable transmission to rotate said ironing member and to engage said station clutch transmission to move said shoe against said ironing member, and in another position of said pedal to disengage said rotating transmission to maintain said rotatable ironing member stationary and to engage said station clutch transmission to cause said shoe to be against said ironing member, and indexing means effective to convey to the user's foot sensations for proper stopping positions of said pedal.

8. An ironing machine comprising a rotatable ironing member, a plurality of shoe members movable to and away from said rotatable ironing member, a motor, transmission means connecting said motor, rotatable ironing member and shoe members, a single foot operated control means having at least three positions, one to cause said roll to remain stationary and all of said shoe members to be out of contact with said rotatable ironing member, another position to cause said motor through said transmission means rotatably to drive said rotatable ironing member and selectively or simultaneously to move said shoe members to and away from said rotatable ironing member, another position to cause a change in the operation of said roll while at least one of said shoe members is in contact with said roll and indexing means cooperating with said control means and effective to convey to the user's foot sensations for proper stopping positions of said single control means.

9. An ironing machine comprising a rotatable ironing roll member, a shoe member, means to cause relative closing and opening movement between said roll member and shoe member, a

motor, a worm transmission driven from said motor, selectively effective gears connected to said worm transmission and said rotatable ironing member, a station clutch connected to said worm transmission and controlling the relative closing and opening movement between said roll member and said shoe member, and a single control means selectively to control in one position the rotation of said roll through said gears and the relative closing movement between said roll member and said shoe, and in another position to maintain said roll stationary and control the relative closing movement between said roll member and said shoe.

10. An ironing machine comprising a rotatable roll, a large shoe, a small shoe, said shoes having ironing surfaces alignable substantially into a unitary ironing surface, rockable supports for

15 said shoes in the rear of said roll, individual control levers for said shoes to render said rockable supports effective or ineffective to bring both shoes or one shoe in ironing contact with said roll, a motor, an engageable and disengageable rotation transmission between said motor and roll, an engageable and disengageable rocking transmission between said motor and rockable supports, and a single control member effective in one position to cause said rotation transmission and rocking transmission to rotate said roll and to rock said rockable supports and in another position to disengage said rotation transmission and cause said rocking transmission to maintain said rockable supports in shoe and roll engaging position.

DONALD K. FERRIS.

It is hereby certified that error appears in the printed specification of the above numbered patent requiring correction as follows: Page 4, first column, line 20, claim 1, for the words "to cause said ironing members to be" read --urging said ironing members--; and second column, line 29, claim 6, and line 47, claim 7, for "to cause said shoe to be" read --in such manner that the shoe is urged--; page 5, second column, line 12, claim 10, after "supports" insert --into a pressure applying position--; and that the said Letters Patent should be read with this correction therein that the same may conform to the record of the case in the Patent Office.

Signed and sealed this 10th day of April, A. D. 1945.

Leslie Frazer

(Seal)

Acting Commissioner of Patents.

motor, a worm transmission driven from said motor, selectively effective gears connected to said worm transmission and said rotatable ironing member, a station clutch connected to said worm transmission and controlling the relative closing and opening movement between said roll member and said shoe member, and a single control means selectively to control in one position the rotation of said roll through said gears and the relative closing movement between said roll member and said shoe, and in another position to maintain said roll stationary and control the relative closing movement between said roll member and said shoe.

10. An ironing machine comprising a rotatable roll, a large shoe, a small shoe, said shoes having ironing surfaces alignable substantially into a unitary ironing surface, rockable supports for

15 said shoes in the rear of said roll, individual control levers for said shoes to render said rockable supports effective or ineffective to bring both shoes or one shoe in ironing contact with said roll, a motor, an engageable and disengageable rotation transmission between said motor and roll, an engageable and disengageable rocking transmission between said motor and rockable supports, and a single control member effective in one position to cause said rotation transmission and rocking transmission to rotate said roll and to rock said rockable supports and in another position to disengage said rotation transmission and cause said rocking transmission to maintain said rockable supports in shoe and roll engaging position.

Patent No. 2,363,518.

November 28, 1944.

DONALD K. FERRIS.

It is hereby certified that error appears in the printed specification of the above numbered patent requiring correction as follows: Page 4, first column, line 20, claim 1, for the words "to cause said ironing members to be" read --urging said ironing members--; and second column, line 29, claim 6, and line 47, claim 7, for "to cause said shoe to be" read --in such manner that the shoe is urged--; page 5, second column, line 12, claim 10, after "supports" insert --into a pressure applying position--; and that the said Letters Patent should be read with this correction therein that the same may conform to the record of the case in the Patent Office.

Signed and sealed this 10th day of April, A. D. 1945.

Leslie Frazer

(Seal)

Acting Commissioner of Patents.
